CLAIM

The ornamental design for sport eyeglasses, as shown.

DESCRIPTION

The file of this patent contains at least one drawing executed in color. Copies of this patent with color drawings will be provided by the Patent and Trademark Office upon request and payment of the necessary fee.

FIG. 1 is a top front perspective view of sport eyeglasses showing my new design;

FIG. 2 is a perspective view of the left side thereof;

FIG. 3 is a perspective view of the top and rear thereof;

FIG. 4 is a bottom view thereof;

FIG. 5 is a left, rear perspective view thereof;

FIG. 6 is a rear perspective view thereof with one arm folded;

FIG. 7 is a bottom, rear perspective view thereof;

FIG. 8 is a front, top left perspective view thereof;

FIG. 9 is a second embodiment of a top front perspective view similar to FIG. 1 with a soft spacer attached to the upper part of the glass frame thereof; and,

FIG. 10 is a rear view of the second embodiment thereof.
